US00D820440S

(12) **United States Design Patent** (10) Patent No.: **US D820,440 S**
(45) Date of Patent: **** Jun. 12, 2018**

(54) **MEDICAMENT DELIVERY DEVICE**

(71) Applicant: **Carebay Europe Ltd.**, Sliema (MT)

(72) Inventors: **Natalia Chuvashova**, Nacka (SE);
Thomas Bergens, Ingaro (SE); **Anders Wieselblad**, Stockholm (SE)

(73) Assignee: **Carebay Europe Ltd.**, Sliema (MT)

(**) Term: **15 Years**

(21) Appl. No.: **29/567,885**

(22) Filed: **Jun. 13, 2016**

(57) **CLAIM**

We claim the ornamental design for a medicament delivery device, as shown and described.

DESCRIPTION

FIG. 1 is a top plan view of the claimed design;

FIG. 2 is a front elevation view thereof;

FIG. 3 is a right side elevation view thereof;

FIG. 4 is a bottom elevation view thereof;

FIG. 5 is a bottom perspective view thereof; and,

FIG. 6 is a perspective view thereof.

The ornamental design which is claimed is shown in solid lines in the drawings.

The broken line showing of medicament delivery device is included for the purpose of illustrating portions of the "article" and forms no part of the claimed design.

1 Claim, 6 Drawing Sheets

See application file for complete search history.
